UNITED STATES PATENT OFFICE.

ANDREW V. GROUPE, OF PHILADELPHIA, PENNSYLVANIA.

ADJUSTABLE DOLL'S EYE.

1,370,889.

Specification of Letters Patent.

Patented Mar. 8, 1921.

Application filed September 3, 1920. Serial No. 407,918.

To all whom it may concern:

Be it known that I, ANDREW V. GROUPE, a citizen of the United States, residing at Philadelphia, in the county of Philadelphia and State of Pennsylvania, have invented 5 certain new and useful Improvements in Adjustable Dolls' Eyes, of which the following is a specification.

This invention relates to improvements in 10 adjustable eyes for dolls and other figure toys.

The object of the invention is to provide 15 an eye device of novel, simple, efficient and inexpensive construction which may be readily adjusted to properly locate the pupils and irises of the eyes within the eye openings in a doll's head, and which may be readily fitted and adjusted to a doll's head to cause the eyes to turn properly within the 20 eye openings of the head to produce the well known sleeping and waking effects when the doll is moved from an upright to a recumbent position and back again.

The invention is characterized by the employment therein of eyes of spherical or approximate or partial spherical form and a shaft carrying the eyes and having its axis 25 piercing the center points of the eyes and constituting the turning axis thereof for the production of the sleeping and waking effects, in combination with means to permit each eye to be adjusted independently of the other not only toward and from each other longitudinally of the shaft and about 30 or around the axis thereof but also about or around an axis which pierces the center point of the spherical eye and pierces the axis of the shaft at right angles thereto; so that each eye may be turned on the axis of 35 the shaft to raise or lower its pupil and iris relatively to its opening in the doll's head without moving the center point of the eye away from the axis of the shaft, and so that each eye may be turned on its aforesaid axis 40 which is at right angles or normal to the axis of the shaft to adjust or turn its pupil and iris toward either end of its opening in the doll's head without moving the center point of the eye away from or longitudinally 45 of the axis of the shaft. It follows, therefore, that during and after any adjustment of either or both eyes the center points thereof will remain on the axis of the shaft and that when the shaft is mounted in a doll's 50 head so that the eyes will turn on the axis

thereof for the sleeping and waking effects, the spherical eyes will turn true in their openings in the head without moving toward or from the wall of the head forming the eye openings.

One of the important features of my invention which I claim broadly is the provision between each eye and the shaft therefore of a positive pivotal connection, the axis of which extends at right angles or normal to and pierces the axis of the shaft in combination with means to retain the eye in different positions of adjustment relatively thereto for the prevention of the shifting of the center point of the spherical eye from the axis of the shaft when the eye is adjusted by turning it either to the right or to the left to set the pupil and iris thereof properly between the ends of the eye opening in the doll's head.

With the foregoing and related objects in view, the invention consists in the novel construction, combination and arrangement of parts hereinafter described and claimed.

In the accompanying drawings, illustrating my invention,

Fig. 1 is a vertical section through a doll's head provided with an adjustable eye structure embodying my invention.

Fig. 2 is a front view thereof.

Fig. 3 is a front view of the eye structure removed from the doll's head.

Fig. 4 is a rear view of the eye structure.

Fig. 5 is a detail, showing the bendable member for connecting the eyes.

Fig. 6 is a horizontal section through the eyes and adjacent parts, on line 6-6 of Fig. 3.

Fig. 7 is a vertical section through one of the eyes on line 7-7 of Fig. 3.

Fig. 8 is a section through the bendable member for connecting the eyes, on line 8-8 of Fig. 5.

Fig. 9 is a rear view of one of the outer shells of the eyes.

Fig. 13 is a side view of one of the members carried by one of the parts shown in Fig. 11.

Fig. 14 is a rear view of an eye structure, showing a modified form of embodiment of the invention.

Fig. 15 is a vertical section on line 15—15 of Fig. 14.

Fig. 16 is a horizontal section, on line 16—16 of Fig. 14.

Fig. 17 is a rear view of an eye structure, showing another form of embodiment of the invention.

Figs. 18, 19 and 20 are sections, on lines 18—18, 19—19 and 20—20, respectively, of Fig. 17.

Fig. 21 is a top view of a modified form of the bendable connecting member for the eyes, shown in Fig. 5.

Fig. 22 is a rear view of the parts shown in Fig. 21.

Referring to Figs. 1 and 2 of the drawings, 2 designates a doll's head in which the eye structure is mounted. The head 2 is of usual, hollow form, being open at the top and at the bottom to afford access to the interior thereof and for lightness of construction, and being provided with the usual eye openings 3 in the forward or face portion thereof.

I shall first describe the form of embodiment of my invention illustrated in Figs. 1 to 13, inclusive; and, referring thereto, 4 designates the eyes of a pair which are fitted to turn in the openings 3 formed in the wall of the head 2. For convenience of manufacture, each eye 4 comprises an outer shell 5 of partial or approximate spherical form, and an inner part 9, the shell 5 and part 9 being secured together and forming, in effect, an integral structure, as will hereinafter appear.

40 The outer shell 5 simulates the natural eye for the doll, being provided with a pupil 10 and an iris 11 on a white field, and it may be constructed of any suitable material. The general structure of the shell 5, excepting as hereinafter described, may be substantially the same as disclosed in United States Letters Patent Nos. 1,187,926 and 1,221,589.

45 The eyes 4 are connected by a part or member 12 which is formed of a single piece of suitable sheet metal and comprises a bottom ring or plate 13, arms 14 diverging upwardly and outwardly from said plate, heads 17 on the upper ends of the arms 14, and 50 projections 21 extending upwardly from the tops of the heads 17. The heads 17 are cupped to receive and fit against the rearward portions of the shells 5; and the shells 5, parts 9 and connecting member 12 are 55 firmly secured together by screws 22 which penetrate the heads 17 and shells 5 and are screwed into the parts 9, the heads of the screws 22 engaging the heads 17 and clamping them and the rearward portions of the 60 shells 5 together and against the inner parts 65

9 of the eyes 4. The arms 14 have an undulant or sinuous form which may be bent in all directions and which normally retain their original or any other form to which they may be bent, as and for purposes hereinafter explained.

70 The lower end portion of the connecting member 12 for the eyes 4 is provided with a relatively heavy weight 23 formed of lead or other suitable material. This weight 23 penetrates the plate or ring 13 of the member 12 and is firmly locked thereto by having parts thereof engaging opposite faces of the plate 13.

75 The inner parts 9 of the eyes 4 are made hollow for lightness of construction and to provide large central openings 24 therein; and each part 9 is pivoted on a member 25 which extends vertically through the eye 4 containing the part 9 and has its upper and lower end portions fitted to bearings in the top and bottom of the part 9, to permit the part 9 and its shell 5 to be turned about the vertical axis of the member 25, for adjusting purposes hereinafter explained. The members 25 are in the form of round pins of uniform diameter throughout their lengths; and vertical displacement thereof within the parts 9 is prevented by the engagement 90 of the ends of the members 25 with the inner walls of the shells 5.

95 Extending centrally between and into the eyes 4 is a round shaft 26, the end portions of which extend through horizontal slots 27 in the walls of the shell 5 and enter the 100 openings 24 in the parts 9 and extend through and beyond the central portions of the members 25. The shaft 26 is fitted to round openings in the members 25 in a manner to permit them to be moved longitudinally of the shaft and to be turned about the axis thereof independently of each other.

105 The shaft 26 is carried by a centrally arranged bracket 28 having a bearing or bearings 29 through which the shaft extends. 110 The bracket 28 carries all the remaining parts of the eye structure and it is adapted to be secured to the inner wall of the head 2, with the eyes 4 in proper position within the openings 3, by any suitable means, such as 115 shellac, or other cement, shown at 30 in Fig. 1. The bracket 28 may extend only upwardly from the bearings 29, as shown by full lines in the drawings, or it may extend downwardly also from the bearings 29, as 120 shown by dot-and-dash lines, at 31, in Figs. 1 and 3; and, when the bracket 28 extends both upwardly and downwardly from the bearings 29, both the upper and lower end portions thereof may be secured to the head 125 2 by cement.

When the bracket 28 is secured in place within the head 2 with the eyes 4 in proper position within the openings 3, the eyes 4, their connecting member 12 and the mem- 130

- bers 25 carrying the eyes 4 are adapted to turn about the axis of the shaft 26, and, during such turning, the member 25 may turn on the shaft 26, or the shaft may turn 5 in its bearings 29 while no relative movement occurs between the members 25 and the shaft 26, or the members 25 may turn on the shaft 26, and the shaft 26 may turn in its bearings 29 at the same time.
- 10 The gravity action of the weight 23 turns the eyes 4 about the axis of the shaft 26 when the doll carrying the head 2 is moved from an upright to a recumbent position and back again, for the closing and opening of 15 the eyes 4, in the usual well known manner. The movement of the eyes 4 to the open position is limited by the engagement of the weight 23 with the cement pad 32 in the head 2, and the movement of the eyes 4 to 20 the closed position is limited by the engagement of the projections 21 with the wall of the head 2 above the eye openings 3.

In assembling the parts of the eye structure shown in Figs. 1 to 13, inclusive, the 25 members 25 are placed within the parts 9, and the members 25 and parts 9 are placed within the shells 5. The parts 9 and members 25 may be placed into the shells 5 by opening the rearward portions thereof, or 30 they may be placed into the shells 5 before the operation of turning inwardly the rearward portions of the shells in the formation thereof takes place. The latter method is preferred, because the shells 5 are stiff, 35 and if the parts 9 are reasonably wide or large, it is not easy to open the rearward portions of the shells sufficiently to permit the insertion of the parts 9. After the parts 9 and members 25 are placed within 40 the shells 5, the ends of the shaft 26 which was previously passed through the bearings 29 of the bracket 28, are passed through the slots 27 in the shells 5 and into the openings in the members 25. The heads 17 of the 45 connecting member 12 are then placed against the rearward portions of the shells 5, and the screws 22 are inserted and tightened.

After the parts have been assembled, as 50 shown in Figs. 3 to 7, inclusive, it is not necessary to loosen the screws 22 to make any adjustments of the eyes. The shells 5, parts 9, connecting member 12 and screws 22 are, in effect, a solid, integral structure. 55 By bending their connecting member 12 and sliding the members 25 on the shaft 26, the eyes 4 may be adjusted toward or from each other, or the eyes 4 may be independently adjusted about the axis of the shaft 26 by 60 bending the member 12 and turning the eyes 4 and their members 25 around the shaft 26, or the eyes 4 may be independently adjusted about the axes of their members 25 by bending the member 12 and turning the 65 eyes 4 on the members 25.

Dolls' heads are not made uniform in many instances and it is frequently necessary to adjust the eye structures therefor in many ways to cause the eyes properly to turn in close proximity to the walls of the 70 openings 3.

In adjusting the eye structure, shown in Figs. 3 to 7, inclusive, properly to fit a doll's head, the eyes 4 are adjusted toward or from each other longitudinally of the shaft 75 26 by bending the member 12 and sliding one or both of the members 25 on the shaft 26 until the eyes 4 will enter and fit the openings 3 and turn therein in close proximity to the walls thereof about the axis of 80 the shaft 26. This adjustment is made before the bracket 28 is secured within the head 2. To adjust the eyes 4 so that the pupils and irises thereof will be set properly between the tops and bottoms of the openings 3, the member 12 is bent to turn the members 25 on the shaft 26 independently of each other until the up and down adjustments of the pupils and irises have been accomplished; and to adjust the eyes 4 85 so that the pupils and irises will occupy proper positions between the ends of the openings 3, the member 12 is bent to turn the eyes independently of each other on the members 25 until the lateral adjustments 90 of the pupils and irises have been accomplished.

The up and down and lateral adjustments of the pupils and irises may be done by taking hold of the projecting heads of the 100 screws 22 and operating them as levers to bend the member 12 and adjust the eyes, and this may be done before or after the bracket 28 has been permanently secured in place within the head 2.

The material of which the connecting member 12 is made is soft enough to permit the bending thereof by the application of reasonable force for the adjustment of the eyes, and hard and rigid enough to maintain the shells 5, parts 9, and members 25 in fixed relative positions for all practical purposes after the adjustments have been made. Before and after the adjustments have been made, the connecting member 12 110 115 prevents the members 25 from turning relatively to each other about the axis of the shaft 26.

The axis of the shaft 26 pierces the center points of the spherical eyes 4, and the longitudinal axis of each member 25 pierces the center point of its eye and also pierces the axis of the shaft 26 and extends at right angles or normal thereto. In other words, the axes of the shaft 26 and each member 25 120 125 meet and cross each other at the center point of the spherical eye 4. These are important features of construction because, when the eyes 4 are adjusted toward and from each other so that they will properly fit the open- 130

ings 3 to turn therein on the axis of the shaft 26, the center points of the spherical eyes 4 will not be moved from the axis of the shaft; and because, when the eyes 4 are turned on the axis of the shaft 26 to raise or lower the pupils and irises of the eyes relatively to the openings 3, the center points of the spherical eyes 4 will not be moved from the axis of the shaft 26; and because, when the eyes 4 are turned on the axes of the members 25 to turn their pupils and irises toward or from the ends of the openings 3, the center points of the spherical eyes 4 will not be moved either toward or from each other or away from the axis of the shaft 26; all of which insures the proper turning of the eyeballs within the eye openings and in close proximity thereto when the doll is moved from an upright to a recumbent position and back again after any or all of the eye adjustments have been made.

In the modification shown in Figs. 14, 15 and 16, the connecting member 33 for the eyes instead of being provided with the heads 17 is provided with hollow, approximately hemi-spherical heads 34 which are fitted within the backs of approximately hemispherical outer shells 35 which simulate the natural eyes. The heads 34 are formed integral with the connecting member 33 which, in other respects, is the same as shown in Figs. 1 to 13, inclusive; and the shells 35 may be secured to the heads 34 by being cemented thereto or by having their edges turned inwardly back of the edges of the heads 34, as shown, or both. The heads 34 correspond with the parts 9, and they are provided with stop projections 36 which correspond with the stop projections 21. Members 37 which support the heads 34 and turn therein are provided to correspond with the members 25; and a shaft 38 and bracket 39 are provided to correspond with the shaft 26 and bracket 28, previously referred to. It will thus be understood that the structure shown in Figs. 14, 15 and 16 may be mounted in a doll's head and adjusted substantially the same as the structure illustrated in Figs. 1 to 13, inclusive.

In the modification shown in Figs. 17 to 20, inclusive, the shaft 40 and bracket 49 are substantially the same as shown in the constructions previously described, the shells 41, heads 42 and members 43 are substantially the same as the shells 35, heads 34 and members 37 shown in Figs. 14, 15 and 16, excepting that the members 43 are secured to the shaft 40 by set screws 44 and that the heads 42 are connected to the shaft 40 by bendable arms 45 instead of being connected together by a bendable member. The arms 45 are formed integral with the heads 42 and are shaped as shown in the

drawings and extend from the heads 42 and embrace the shaft 40 in a manner to permit them to be moved longitudinally and to be turned about the axis of the shaft 40 independently of each other with the heads 42 and their shells 41. The shaft 40 is provided with a centrally-arranged, downwardly-extending arm 46 carrying a weight 47 as the means for turning the shaft 40 and eyes 41 when the doll is moved from an upright to a recumbent position and back again; and the arm 46 has an upwardly-extending projection 48 which is adapted to engage the bracket 49 and limit the movement of the eyes when the doll is moved to the recumbent position. When it is desired to adjust the eyes 41 toward or from each other or about the axis of the shaft 40, independently of each other, the set screws 44 are loosened to permit the adjustments to be made and then tightened, causing the eyes 41 and shaft 40 to turn as a unit. When it is desired to adjust the eyes 41 to turn the pupil and irises thereof laterally, the same may be done by bending one or both of the arms 45 and turning one or both of the heads 42 about one or both of the members 43. The bendable arms 45 will retain the pupils and irises of the eyes in positions of lateral adjustment relatively to the shaft 40 after they have been moved thereto.

In Figs. 21 and 22, I have shown a modification of the connecting member 12 for the eyes shown in Figs. 1 to 13, inclusive. In this modification, a T-shaped piece, comprising the horizontal member 50 and vertical member 51, connects the plate or ring 13 and heads 17, instead of the arms 14, and the horizontal member 50 is provided with rearwardly bowed portions 52 which permit it to be bent to effect the adjustments for the eyes hereinbefore described.

I claim as my invention:

1. The combination of a shaft, an eye, means to pivotally connect the eye to the shaft on an axis which is substantially normal to and intersects the axis of the shaft, and means to prevent the turning of said eye in either direction about the first named axis from different positions of adjustment thereon.

2. The combination of a shaft, a member carried by the shaft, an eye pivoted on the member and adjustable thereon about the axis of its pivot, and means to retain the eye in different positions of adjustment relatively to the member.

3. The combination of a shaft, a member carried by the shaft, an eye pivoted on the member and adjustable thereon about the axis of its pivot, and means cooperating with the shaft to retain the eye in different positions of adjustment relatively to the member.

4. The combination of a shaft, a member carried by the shaft, an eye pivoted on the member on an axis which is normal to and intersects the axis of the shaft, and means to retain the eye in different positions of adjustment relatively to the member, said eye having a partial spherical form the center of which is in the region of the intersection of said axes.
- 10 5. An eye comprising an outer shell and an inner part on which the shell is mounted, in combination with a shaft, a member carried by the shaft and on which said part is pivotally mounted, said eye being adjustable about the axis of the pivotal connection between said member and said part, and means to retain said part in different positions of adjustment relatively to said member.
- 20 6. The combination of a hollow eye having an opening in one side thereof, a shaft extending into the eye through said opening, a member carried by the shaft, said eye being pivoted on said member and adjustable thereon about the axis of its pivot, and said opening permitting the adjustment of the eye relatively to the shaft, and means to retain the eye in different positions of adjustment relatively to the member.
- 30 7. The combination of a shaft, two spaced members carried thereby, each member having an eye pivoted thereto on an axis which is normal to and intersects the axis of the shaft, the eyes being adjustable about the axes of their pivots relatively to each other and to said members, and means to retain the eyes in different positions of adjustment relatively to each other and to said members.
- 40 8. The combination of a shaft, two spaced members slidable on said shaft toward and from each other, each member having an eye pivoted thereto on an axis which is normal to and intersects the axis of the shaft, the eyes being adjustable about the axes of their pivots relatively to each other and to said members, and means to retain the eyes in different positions of adjustment relatively to each other and to said members at different distances apart on said shaft.
- 50 9. The combination of a shaft, two spaced members carried by said shaft and adjustable independently of each other about the axis thereof, each member having an eye pivoted thereto on an axis which is normal to and intersects the axis of the shaft, the eyes being adjustable about the axes of their pivots relatively to each other and to said members, and means to retain the eyes in different positions of adjustment relatively to each other and to said members and to retain said members in different positions of relative adjustment about the axis of said shaft.
- 10 10. The combination of a shaft, two spaced members slidable on said shaft to adjust them toward and from each other and rotatable on said shaft to adjust them independently of each other about the axis thereof, each member having an eye pivoted thereto on an axis which is normal to and intersects the axis of the shaft, the eyes being adjustable about the axes of their pivots relatively to each other and to said members, and means to retain said members in different relative positions of adjustment on said shaft and to retain the eyes in different positions of adjustment relatively to each other and to said members.
- 20 11. The combination of a pair of eyes, a shaft therefor, connections between said eyes and shaft permitting said eyes to be adjusted relatively to each other and to said shaft, and means connecting said eyes and normally preventing relative movement between them and being bendable to adjust said eyes relatively to each other and to said shaft.
- 30 12. The combination of a pair of eyes, a shaft therefor, connections between said eyes and shaft permitting said eyes to be adjusted relatively to each other and to said shaft, means connecting said eyes and normally preventing relative movement between them and being bendable to adjust said eyes relatively to each other and to said shaft, a bracket carrying said shaft, and a weight carried by said means for causing relative movement between the eyes and the bracket about the axis of the shaft when the bracket is turned.
- In testimony whereof I affix my signature hereto.

ANDREW V. GROUPE.
